UNITED STATES PATENT OFFICE.

ALFRED L. RUTHVEN, OF ROCHESTER, NEW YORK, ASSIGNOR TO SIMPLEX TRAIN CONTROL COMPANY, INC., OF ROCHESTER, NEW YORK, A CORPORATION OF NEW YORK.

ELECTROMAGNETIC TRAIN-CONTROL AND DANGER-INDICATING MEANS AND RECORDING MEANS.

1,374,954.

Specification of Letters Patent. Patented Apr. 19, 1921.

Application filed October 8, 1918. Serial No. 257,336.

To all whom it may concern:

Be it known that I, ALFRED L. RUTHVEN, a citizen of the United States, and resident of Rochester, in the county of Monroe and State of New York, have invented certain new and useful Improvements in Electromagnetic Train-Control and Danger-Indicating Means and Recording Means, set forth in the annexed specification.

10 The present invention relates to rail road block signaling and automatic train or vehicle control, and is particularly an improvement over the electrical track circuit control disclosed in the copending application for

15 Patent, Serial No. 215,300, filed Feb. 4, 1918.

It is the object of the invention to provide novel and improved means of coöperation between the vehicle and track equipments for controlling the movement of the vehicle

20 under the various traffic conditions, such means eliminating the use of electrical, mechanical or other contact or similar devices between the vehicle and track, thereby removing a serious objection to train controlling apparatus embodying such contact devices.

25 Another object is the provision of such means between the vehicle and track or road bed utilizing magnetic force in a novel manner as the medium of control, to dispense with contact and like devices and their objectional characteristics.

30 A further object is to provide novel magnetic means on the track for influencing the vehicle equipment, having improved features to enhance its utility.

35 Another object is the provision of an improved magnetically responsive vehicle equipment controlling the movement of the vehicle, and also bringing the vehicle to a stop or retarding its movement should the equipment not be in operative condition, thereby preventing the vehicle from proceeding when its controlling means is defective.

40 A still further object is to improve the vehicle equipment so as to effectively retard the vehicle when danger is presented, and to permit the vehicle to proceed under caution at a slow speed, stopping it if the speed allowed is exceeded. This permits the vehicle to move, under the direction of the authorized person, after danger is signaled and the power shut off and brakes applied

automatically through the magnetic appliances, so that the operator can proceed with 55 the vehicle or back up, such as for the purpose of moving into a siding for clearing the main line, or the like.

The invention also includes novel means for clearing the vehicle when proceeding 60 under caution conditions, so that the impediment as to retarded speed is removed, and the vehicle again allowed to proceed unrestricted, but only when normal danger conditions are positively changed to clear 65 conditions to avoid accidental clear signals.

Furthermore, the invention has for an object the provision of novel means for giving danger and clear signals on the vehicle, and keeping a record of the operation of the controlling means for subsequent inspection.

Another object is to provide novel and improved means for operating the engineer's brake valve automatically, and allow him to apply the brakes at any time but not release 75 them in danger conditions.

With the foregoing and other objects in view, which will appear as the invention is more fully understood, the invention resides in the construction and combination of parts 80 as hereinafter described and claimed, it being understood that changes can be made within the scope of what is claimed without departing from the spirit of the invention.

The invention is illustrated in the accompanying drawing, wherein—

Figure 1 is a general view of the apparatus, mostly in diagram;

Fig. 2 is a longitudinal vertical section of the magnetically responsive mechanism of 90 the vehicle, taken on about the line 2—2 of Fig. 1;

Fig. 3 is a perspective view of the track equipment, part of the casing being broken away to show the interior mechanism;

Fig. 4 is a transverse section of the track device, showing it more in detail and in normal danger position; and

Fig. 5 is a diagrammatical view of a block signal system of simple circuits, with the present apparatus linked or connected thereto to provide the connecting medium between the ordinary block signals and controlling means on the vehicle.

The apparatus is used on the locomotive 105 of a train or other vehicle and the track or

road bed, and controls the usual air brake system, which includes the air reservoir 1 from which the air flows through the engineer's brake valve 2, when permitted, to the 5 brake or train pipe 4^a so as to supply the auxiliary reservoirs as usual. When the brake valve is moved to another position by means of its handle 3, the air escapes from the brake pipe 4^a to the atmosphere through 10 the port 4 thereby applying the brakes. The apparatus forming the present invention includes means for automatically operating the brake valve 2, among other controlling means, and the various devices will be described 15 separately under their respective captions.

Vehicle stopping control.

The apparatus embodies a main control 20 for bringing the vehicle stopping or retarding means into operation, and this control, designated generally at 5, see Fig. 1, is housed in a suitable casing 6 having the door 6^a for gaining access to the parts for 25 purpose of repair, inspection, or the like. The door 6^a is under lock and key and has a window to make the parts visible to the operator or engineer.

Within the casing 6 is a main air valve 7 30 of the control having the stem 8 disposed horizontally, and any suitable oscillatory valve can be used. A recording device 9 is connected to the valve 7 so as to record the number of operations thereof for subsequent 35 inspection, and to thus keep an automatic check on the operator.

The valve 7 has connected thereto a pipe 11' leading from a speed control device 10 hereinafter described, to receive air from a 40 pipe 21 leading to the device 10 from the air reservoir 1 or other source of fluid pressure, and the valve 7 is normally closed to prevent the flow of air past it, but the air is ready to flow through said valve the instant 45 that it opens. Said valve is a three way valve and has connected thereto another pipe 11 and also a pipe 12 which are connected together and in communication. The pipe 12 has branches leading to a 50 whistle or audible signal 35, visual signal 34, power interrupting means 13, and the brake valve operating means 25, and the valve 7 when in normal position connects the pipe 11 through the valve with the atmosphere, thereby permitting the air to escape from the pipe 12 and said signals and means. The signal 34 therefore normally indicates "clear", being operated pneumatically, and the means 13 and 25 are 55 released for ordinary operation, both being under pneumatic control through the pipe 12. When the valve 7 is turned, however, it closes the escape port from the pipe 11, and establishes communication between the 60 pipes 11' and 12, so that air flows at once 65

to the signals and indicates, audibly and visually, "danger", and the air also flows to the power interrupting means 13 to operate same for cutting off the steam or other motive power of the vehicle. At the same 70 time the air flows to the device 25 for turning the brake valve 2 forcibly, even against the resistance on the part of the operator if he tries to stop the action, so as to apply the brakes, and bring the vehicle to a halt. 75

An arm 23 having a weight is carried by the valve stem or shaft 8 and is normally raised, so that said arm will swing downwardly by gravity and turn the valve 7 to stop the vehicle, when said valve is released, 80 the weighted arm 23 being always ready to operate said valve when needed. A second arm 24^a is also attached to the stem 8 and is connected to the core of a solenoid or electro-magnet 24 that is normally energized to raise the arms 23 and 24^a and retain the valve 7 in normal position. Should the solenoid or magnet 24 become dead by the operation of the apparatus or by accident thereto, the arm 23 is heavy enough to 90 operate the valve 7 under any condition and therefore stop the vehicle as described above. The reenergization of the solenoid again raises the arms 23 and 24^a to again restore the valve 7 to normal clear position. The 95 solenoid 24, arms 23 and 24^a, recorder 9, and signals are all located within the casing 6 so as not to be interfered with.

Speed control device.

The device 10 which is operative under caution conditions for controlling the speed at which the vehicle may proceed, includes a body 14 having an oscillatory valve 16 mounted therein and provided with a handle 16^a that can be swung by the authorized person after a danger signal is given and the vehicle stopping means brought into play. A passage 15 in the body 14 connecting the pipes 21 and 11' is normally closed 105 by the valve 16 but a second passage 22 also connecting said pipes is normally open through said valve, said passages being alternately opened for clear and caution conditions. A valve rod 17 slidable in the body 14 also normally closes the passage 15 and has a port 18 to register with said passage when said rod is moved by excess speed. A piston 19 on the rod 17 moves within a cylinder 20 in the body 14 and a spring 19^a 110 normally retracts the rod 17 and closes the passage 15 and opens another passage 12' in the body connecting the pipe 12 with the atmosphere. Passages 31 and 32 in the body 14 communicate with the rear end of the 115 cylinder 20 and are controlled by the valve 16, the passage 32 opening into the atmosphere and the passage 31 communicating with the air supply passage 22 at the reservoir side of the valve 16. Another pair of 120 130

passages 33^a and 33 in the body 14 communicate with the other end of the cylinder 20 and are controlled by the valve 16, the passage 33 leading to the atmosphere and the 5 passage 33^a communicating with the passages 15 and 22 at that side of the valve 16 opposite to the reservoir connections. In normal position the valve opens the passages 32 and 33^a and closes passages 31 and 10 33, thereby letting air into the forward end of the cylinder and out of the rear end thereof so that the air moves the piston backward and retracts the valve rod 17 assisted by the spring 19^a, but when the valve 16 is 15 turned by the handle 16^a, passages 32 and 33^a are closed and passages 31 and 33 opened, so that the air can escape from the forward end of the cylinder and is admitted into the rear end thereof to exert continued pressure tending to push the piston 19 and valve rod 17 forward. The valve rod 17 is thus controlled and operated pneumatically according to the position of the valve 16.

A governor 37 of any suitable sort is used 20 to control the speed under caution conditions, and is connected by means of a sprocket chain 37^a, gearing 37^b, or the like with a wheel or other part of the vehicle which rotates when it is in motion. The 25 parts 37^a or 37^b can be taken to represent means which rotate during the motion of the vehicle to rotate the governor according to the speed of the vehicle. The governor controls the valve rod 17 through the medium of a rocking lever 38 having one arm operatively connected to the governor 37 and its other arm in the path of the forward end of the rod 17 to prevent its forward movement unless the vehicle exceeds 30 a certain predetermined speed which will cause the lever 38 to be swung sufficiently to release the rod 17. The end of the rod 17 preferably has a roller 38^a to contact with the lever or latch 38 and reduce friction. As a result, when the lever or handle 45 16^a is swung to proceed under caution, so that the flow of air through the passage 22 to the means 13 and 25 is stopped and the air allowed to escape therefrom through the 50 passage 12', thereby permitting movement of the vehicle, the air now tends to advance the piston 19 and rod 17, but this is prevented by the lever or detent 38 unless the allotted speed is exceeded when the rod 17 55 can move. This will close the escape passage 12' from the means 13 and 25 and will open the passage 15 so that air flows through this by-pass to the means 13 and 25 to actuate them for again stopping the vehicle. Thus, when proceeding under caution, the speed allowed must not be exceeded, or else the vehicle will be automatically stopped.

This speed control device therefore per-

mits the vehicle to proceed slowly in the 65 danger zone, so that it can proceed or back up at will below a given speed to avoid collision or accident, and at the same time, the operator can not put the automatic means out of control for stopping the vehicle 70 again.

When the track is clear and the valve 7 again returned to normal position, the valve 16 is returned by hand, so that the vehicle 75 can proceed as usual.

Brake valve operating device.

The device 25 has been designed to operate the engineer's brake valve 2 in an effective manner, and includes a cylindrical 80 casing 26 above the brake valve, as shown, and the stem 27 of the brake valve extends up through the lower end of said casing and is connected by a key 27^a within a rotary head 28^a seated upon said lower end of the 85 casing. The head 28^a is rotatable within a ring 30 surrounding it and having a lower outturned flange clamped between the parts of the casing at its lower end, said ring also having an upper flange inturned to overlap 90 the head 28^a and retain it in place. The head 28^a has a stud 28 concentrically within the casing provided with a helical groove 28^b forming a screw entering the central opening of a piston 29 which is slidable in 95 the casing above the member or stud 28. The piston 29 has a pin 29^a entering the groove 28^b and the piston is kept from turning by means of feathers 28^a in the casing 100 engaging grooves in the sides of said piston. An expansion spring 30^a between the ring 30 and piston 29 normally raises said piston and forces the air therefrom through the pipe 12 which is connected to the upper end of the casing 26 that provides a cylinder for the piston. The key 27^a is made fast to the stem 27 and works within a notch or groove in the member or head 28^a so that when the piston 29 is in normal raised position, the stem 27 and handle 3 can turn 105 as usual for applying the brakes, without actuating the parts of the operating device 25, but when the piston is forced down by the flow of air into the upper end of the casing or cylinder from the pipe 12, the pin 110 29^a in traveling in the groove 28^b will turn the head 28^a and thus turn the key 27^a and stem 27 to apply the brakes automatically. In other words, the key 27^a can move forward in the head 28^a but when the head 115 turns in the same direction, the key 27^a when in normal releasing position for the brakes, will be carried with the head as it would be by turning the handle 3 for applying the brakes. In this way, the operating device does not interfere with ordinary 120 operation of the brake valve under clear conditions, but automatically applies the 125

brakes in the event of a danger signal and maintains them applied, until the apparatus is cleared.

Track device.

5 Reference is now had to the device used on the track at the controlling points (see Figs. 1 and 4,) which may be at selected intervals, along the track of which the rails 10 are shown at 36. Each of these devices includes a pair of danger armatures 40 at opposite sides of a clearing armature 39 located at the center of the track, all mounted for up and down movement toward and away 15 from the vehicle, and said armatures are of suitable length. These armatures are mounted within a casing 41 that is of non-magnetic material so as not to interfere with the magnet attraction between the track and 20 vehicle devices, and as shown in Fig. 1 the top of the casing has longitudinal corrugations or depressions between the armatures for stiffening and reinforcing the top of the casing which can therefore be as thin as possible above the armatures. The armatures 25 are carried by transverse crank-shafts 42 journaled within suitable bearings within the casing 41 and said shafts in being rocked will alternately raise the armatures 39 and 30 40 to active position. The casing protects the armatures from damage and interference owing to weather conditions, and the track device is also foolproof. As shown, the track device is operated electrically but it may 35 be controlled mechanically, pneumatically or otherwise. A cup 45 secured to the bottom of the casing 41 holds a solenoid 44 the core of which is connected, as at 43, to one of the rock shafts 42, in order that when the sole- 40 noid is energized, the armatures 40 are moved downwardly to inactive position, and the armature 39 raised to active position, under clear conditions. The armature 39 is heavier than the two armatures 40, in 45 order that when the solenoid 44 is deenergized under normal conditions or by failure of the controlling means, the armature 39 will gravitate to inactive position and raise the armatures 40 thereby presenting danger. 50 Thus, the track device is normally at danger and will go to this position if the controlling means fails, to assure the fact that the track device will not clear the vehicle passing it unless this is the actual condition. 55 Figs. 3 and 4 illustrate the track device more in detail than shown in Fig. 1, and in these views, the inclined ends of the casing 41 are shown, but the corrugations or depressions in the top of the casing are 60 left out, so that their use is made optional. The casing 41 is seated on and supported by one or more transverse supporting bars 100 and each of these bars is attached at its ends to the rails 36 so as to be supported thereby 65 and thereby support the casing 41 and ar-

matures from the rails instead of from the cross ties. In this way, the casing and armatures are maintained in fixed relation to the rails and the responsive vehicle devices which pass over the track device, in order 70 that the relation of the track and vehicle devices will not be varied or disturbed by the yielding movement of the rails and ties under the weight of the vehicle thereon. The ends of the bar 100 pass under the rails 75 36, and said bar is provided near its ends with lips 101 overlapping the base flanges of the rails at the inner sides of said rails, and clamping jaws 102 are bolted or otherwise fastened to the ends of the bar 100 and have 80 lips overlapping the base flanges of the rails on the outside to clamp the bar 100 in place, and permit its removal for purpose of repair. It is preferable to place insulation 103 between the bar 100 and rails 36, and this is necessary when the rails 36 are used 85 as conductors, to prevent short circuit.

Figs. 3 and 4 illustrate the bearings 104 of the rock shafts 43 in the form of pedestals secured on the bottom of the casing 41 90 and bars 100, and said rock shafts embody journal sections 105 and 106 journaled through the bearings 104 and the armatures, respectively, with crank arms 107 secured to the journaled sections 105 and carrying 95 the journaled sections 106 to form the cranks. The journals are preferably of anti-frictional design so that the armatures move freely, and such bearings for the journaled sections 106 are inset in the sides of 100 the armatures, as at 108.

Figs. 3 and 4 also illustrate the lamination of the armatures longitudinally thereof with the laminæ in vertical planes, whereby to avoid stray eddies of the magnetic 105 flux, and to greatly enhance the attraction of the vehicle magnets to said armatures as they pass longitudinally thereover.

The bars 100 not only support the casing 41 above the cross ties with a suitable clearance, to allow the casing to yield with the rails 36, but said bars also serve as stays to prevent the rails from spreading. Attention is also directed to the fact that the construction of the rock shafts 42 enables the 110 cranks thereof to be adjusted angularly relatively to one another by loosening the arms 107 on the journal sections 105.

Responsive vehicle device.

The vehicle equipment has magnetic means responsive to the armatures of the track device, and for this purpose, three electromagnets 46, 47 and 48 are carried by the vehicle for vertical movement, the 115 first one 46 at the center of the track to respond to the armature 39 when raised for clearing the vehicle, the second one 47 above one rail 36 or adjacent to some other magnetic object to be attracted thereto for re- 120 125 130

taining clear conditions, and the other magnet 48 arranged to move over one or the other of the armatures 40, according to the direction of travel, to be attracted thereto 5 for indicating danger and stopping the vehicle. Said magnets are slideable vertically within depending pockets of a casing 49 carried by the vehicle in any suitable manner, and said casing is of non-magnetic material so as not to interfere with the magnetism.

The clearing magnet 46 and clear retaining magnet 47 are movable simultaneously, and to this end a transverse rock shaft 50 is journaled in suitable bearings in the casing 49 and has arms 51 and 53 secured thereto from which the respective magnets 46 and 47 are suspended, the arm 53 being longer than the arm 51, as seen in Fig. 2, 20 whereby the magnet 47 moves a greater distance than the magnet 46. In this way, when said magnets are moved upwardly, the magnet 47 will be sufficiently removed from the rail 36 so as not to be attracted thereto 25 unless the magnet 46 is first attracted to the armature 39 in raised position which will move the magnet 47 closer to the rail 36 into attractive relation thereto, so as to maintain such attraction and retain the magnets 30 46 and 47 in attracted or responsive position, as seen in Fig. 1.

A second transverse rock shaft 57 is also journaled in the casing 49 and has an arm 59 secured thereto from which the magnet 35 48 is suspended, so that said magnet is movable independent of the others. It will be noted that the magnets move bodily up and down, and that their coils or windings move longitudinally of their vertical axes, so as 40 to cause a powerful attraction of the magnets to the armatures over which they pass, when said armatures are in raised position. The rock shafts 50 and 57 (see Fig. 2) have arms 55 and 61, respectively, depending 45 within switch casings 58 and 63, whereby said arms operate electrical switches and also have springs 81 connected thereto, tending at all times to swing said arms and raise the magnets, which will result when- 50 ever the magnets are deenergized. Each of the electrical switches operated by the arms 55 and 61 includes, as shown in Fig. 2 in connection with the arm 55, a switch arm 83 pivoted at its lower end to a base 84 55 having a binding post 85, and the switch arm 83 is connected by an insulating link 88 with the arm 55 (or 61). Adjustable stop screws 82 are carried within the casings 58 and 63 for limiting the movement of the 60 arms 55 and 61, in order that both the upward and downward movement of the magnets can be limited as desired, according to the clearance wanted with respect to the armatures.

65 The switch arm 83 carries a spring con-

tact 86 to engage a contact terminal 87, when the respective magnet is lowered, and said switch arm has a second spring contact 91 to engage an adjustable contact 90 of another terminal member 89 when the respective magnet is raised. Each switch is of this construction, to provide for either a normal open or a normal closed circuit, whichever is used. This permits of either a closed or an open circuit for either switch 70 under normal conditions, and adjustments 75 can be made to suit the circumstances.

The ends of the pockets of the casing 49 containing the magnets are provided with removable points 80 for deflecting stray objects out of the way, and for cutting snow and ice in the winter season.

The electrical circuits of the vehicle equipment are supplied with the electrical energy from a generator 64 or other suitable 85 source. The circuit of the solenoid or magnet 24 of the controlling valve 7 includes generator 64, conductor 60, magnet 24, conductor 68, armature switch 52^a of a safety magnet 52, conductor 69, clear magnet 90 switch, and conductor 65. The conductors 65 and 69 are connected to the binding post 85 and contact terminal 87, respectively, of the clear magnet switch, whereby the switch arm 83 normally connects said conductors 95 when the clear magnet 46 is down, and since the armature switch 52^a is normally closed, the circuit of magnet 24 will be normally closed so as to energize said magnet and raise the weight arm 23 to retain the valve 100 7 in normal position. It is evident that if the current fails, by the opening of either or both of the switches in the circuit for that purpose or by the failure of the vehicle equipment to be in operative condition, 105 the magnet 24 will become dead, thereby releasing the valve stem or shaft 8 and permitting the weight arm 23 to open the valve 7 for the flow of air to the signal devices and train or vehicle retarding means. This 110 assures of the vehicle being given a danger signal and being stopped whenever the circuit of magnet 24 is opened by the apparatus in operation or whenever the apparatus is not in operative condition, such as the failure of current or the like. The clear magnet switch is normally held closed due to the fact that the magnet 47 is attracted to the rail 36 or other magnetic object, thus maintaining clear conditions as long as current 115 flows through said magnet, but if it fails, then the magnets 46 and 47 go up by the force of their lifting spring 81, and the clear magnet switch therefore opens between conductors 65 and 69 and thus opens 120 the circuit.

The magnets 46, 47 and 48 are all normally energized, with the magnets 46 and 47 down and the magnet 48 up, as seen in Fig. 1. One of the circuits includes gener- 125 130

ator 64, conductor 66, normally closed danger magnet switch, conductor 67, safety magnet 52 to keep it energized, conductor 54, magnet 48 in series with magnet 52, and 5 conductor 65. Magnets 48 and 52 are thus normally energized, and failure of current in magnet 48 will also deenergize magnet 52 so that switch 52^a opens and magnet 24 becomes dead. The attraction of the danger 10 magnet 48 to the respective armature 40 in raised position will swing the arm 61 so as to open the danger magnet switch and the circuits thereof, so that all magnets become dead. Thus, the magnet 24 is deenergized 15 either by the release of the normally attracted clear magnets 46 and 47, or by the response of the danger magnet to the track device, providing a double acting arrangement. The conductor 67 has branches connected to 20 the magnets 46 and 47 both in parallel with the magnet 48 and with one another, and the return conductor 65 is also branched and connected to the magnets 46 and 47 to complete the shunt circuits thereof. In the danger 25 magnet switch, the conductor 67, like the conductor 65, is connected to the binding post 85 and switch arm 83, but owing to the difference in the normal position of the magnets of the two sets, the conductor 66 is connected to the terminal member 89 instead of 30 the contact terminal 87 as with the conductor 69. This is done to provide closed circuits for both switches with the magnets 46 and 47 normally down and the magnet 48 35 normally up. Should the current fail in any of the several circuits, a danger signal will be given and the train retarding or stopping means brought into action.

40 Operation.

In Fig. 1, the apparatus is shown in clear condition, the armature 39 being raised to attract the magnet 46, which in being moved downwardly will carry the magnet 47 into 45 attractive relation with the rail 36, so that the magnets 46 and 47 are held down against the tension of their spring 81, as long as said magnets are energized. This maintains clear conditions by holding the clear magnet 50 switch closed, and the magnet 48 although normally energized is held in raised position by its spring 81, so that the danger magnet switch is also normally closed. The vehicle can therefore proceed 55 unrestricted as usual, but should the current fail in any of the circuits, the magnet 24 will naturally become deenergized and the valve 7 will be operated by the weight arm 23, to give the danger signals and operate 60 the power interrupting means 13 and brake valve operating device 25, thus preventing the vehicle from proceeding with a defective controlling apparatus. This same result is obtained should the vehicle pass one of the 65 track devices in normal danger position

without having been moved to clear position. Thus, assuming that the armatures 40 are in raised position, as seen Fig. 4, the magnet 48 in passing over one of said armatures will be attracted thereto and 70 moved downwardly, thereby opening the danger magnet switch between the conductors 66 and 67, and this will open the circuits of all three magnets 46, 47 and 48, as well as the circuit of magnet 52. The circuit of the magnet 24 is therefore opened at two places, viz., at the switch 52^a and at the clear magnet switch between the conductors 65 and 69. The switch 52^a is opened by the responsive movement of the magnet 48, and 75 the clear magnet switch is opened by the release of the magnets 46 and 47 when they are deenergized. This provides for a double action, in that, danger conditions are brought about by either the response of the 80 danger magnet or by the return of normally energized and responding clear magnets 46 and 47. The slightest downward movement of the danger magnet 48 opens the danger magnet switch, so that current will not flow 85 through any of the magnets. The magnet 48 being deenergized after the danger signals are given, will be returned or raised by its spring 81, but the magnets 46 and 47 having also been raised by their spring 81 90 will retain the clear magnet switch open during danger and caution conditions, it being noted that during these conditions, the clear magnets 39 are down so as not to attract the magnet 46, and the magnet 47 is 95 far enough away from the rail 36 or other magnetic object not to be attracted thereto unless the magnet 46 is first attracted and moved downwardly. These conditions will 100 prevail until the apparatus is again cleared. 105

When the valve 7 is operated by the fall of the arm 23 whenever the magnet 24 becomes dead, whether intentionally or accidentally, the air will flow at once to the signal devices 34 and 35 to operate them pneumatically for indicating danger visually and audibly, and the air will then flow to the device 13 for shutting off the steam or other motive power. The air also flows into the upper end of the casing or cylinder 26 so as 110 to force the piston 29 down, and its pin 29^a in working in the groove 28^b will rotate the stud or member 28 and thus operate the brake-valve 2 to vent the brake pipe 4^a and apply the brakes. 115

Should it be desired to proceed under caution conditions, the operator or authorized person can swing the handle 16^a of the speed control device 10, so as to reverse the valve 16. This will close the passage 22 through 120 which the air normally passes from the supply pipe 21 to the pipe 11^a leading to the valve 7, and the passage 12^a is opened, so that the air can pass from the signal device 34, and devices 13 and 25 to the atmosphere. 130

This allows the power to be again applied, and the spring 30^a will raise the piston 29 and return the member 28 so that the operator can release the brakes. The reversal of valve 16, however, opens the passage 15 at that point, and the passage 31 so that the air enters the cylinder 20 and tends to move the piston 19 and valve rod 17 forward, which is prevented by the lever or detent 38, 5 when traveling below a predetermined speed. Should this speed be exceeded the governor 37 being operated by centrifugal force will remove the lever or detent 38 from the end of the rod 17, and the air pressure 10 against the piston 19 will therefore operate at once to move the rod 17 forward and bring the port 18 into register with the passage 15, while the passage 12' is now closed. Air will therefore flow from the pipe 21 15 through the passage 15 to the pipe 11' and valve 7 which remains in danger position. The danger signals are therefore again given and the vehicle stopped. This prevents the vehicle from traveling above the 20 allotted speed in the danger zone, but still permits it to move slowly to pass into a siding or the like. When the vehicle is stopped under caution conditions, the valve 16 can be returned so that the air will again enter 25 the forward end of the cylinder 20 to return the piston 19 and rod 17, as seen in Fig. 1, without releasing the brakes or power interrupting means, and if the vehicle has been stopped or is moving slowly, so that the 30 lever or detent 38 is again in active position, the valve 17 can be reversed again to caution 35 position without stopping the vehicle again unless the speed allowed is exceeded.

The caution and danger conditions will 40 be maintained, until the apparatus is positively cleared, and until such is the case the vehicle must either remain at rest or proceed slowly under caution conditions, as above described. When the track is clear, and a 45 track device which the vehicle passes set to clear position with the armature 39 raised, the magnet 46 in passing therover will be attracted thereto, thereby closing the clear magnet switch which will then be held 50 closed by the magnet 47 remaining attracted to the rail 36. The circuit of the magnet 24 is now closed, because the switch 52^a remains closed when the magnet 48 is raised and energized, and the clear magnet switch is 55 closed by the response of the clear magnet. The valve 7 is therefore returned to the clear position as before, and the vehicle can proceed unrestricted as above described, before the danger signal was given.

60 Block signal system and track devices.

Fig. 5 illustrates the conjunction of a series of the track devices at intervals along the track with a block signal system of simple normal danger arrangement. The rails

65 are divided into the sections A, B, C, D and E insulated from one another, and electrically-operated semaphores 37 are located between the blocks, each of which contains two or more sections. As many track devices can be used as desired, and as shown, they are placed at the junctures of the track sections and between the ends thereof. The signal system illustrated is a well known simple form and includes an electromagnet 70 connected to each pair of rail sections at one end and a track battery 71 connected thereto at the other end to complete a normally closed circuit for each section and maintain the magnet 70 energized. Each 75 magnet 70 attracts and normally closes an armature switch 73 disposed in signal circuits 72 of the semaphores 37, and each of said circuits also includes an armature switch 74 attracted and normally opened by 80 a magnet 70 in rear. Thus, taking one circuit 72, it includes the semaphore 37 between sections B and C, armature switches 73 at the ends at section C, armature switch 74 between section A and B, and the solenoids or magnets 44 of the track devices of the centers and forward ends of the sections B and C. The normally opened switch 74 85 opens the circuit, so that the respective semaphore and track devices or armatures 90 thereof are in normal danger position. This condition will also exist if sections C or D are occupied, because this will short circuit one of the magnets 70 of said sections to let the respective switch 73 open and the opening of the semaphore circuit at any one of the several points will produce danger conditions. However, should a train enter section B, moving toward the left in Fig. 5, the magnet 70 of said section will be short 95 circuited and therefore deenergized, so that its switch 74 will close the circuit and thus move the semaphore and track devices to clear position, whereby the train can advance past the semaphore into the next 100 block. When the train enters section C, the magnets 70 thereof will be deenergized by the short circuit established, and even though switch 74 is again opened as well as switch 73 between sections B and C, a 110 second normally opened switch 75 of the magnet 70 under discussion will be closed by the deenergization of the said magnet 70, and thus close the circuit of the two magnets 44 in advance, so that the train 115 can pass the respective train devices. The switch 75 forms a short circuit between the battery 76 of the circuit 72, and the semaphore 37 and magnets 44 in rear, so that a train following in section B will be stopped 120 because the said semaphore and last mentioned magnets 44 will be at danger, although train already in the block can proceed.

125 This arrangement is just one of many in

which the present track devices can be used for controlling traffic, and the illustration is to be taken as typical to make the invention better understood.

5 Having described the invention, what is claimed is:

1. Vehicle controlling apparatus embodying a controlling device on the track having alternately movable armatures and a rock 10 shaft with cranks for said armatures to actuate them.

2. Vehicle controlling apparatus embodying a controlling device on the track having alternately movable armatures and a rock 15 shaft for actuating them provided with angularly adjustable cranks journaled to said armatures.

3. Vehicle controlling apparatus embodying a non-magnetic casing on the track, 20 bearings therein, controlling armatures for vehicle devices within said casing and movable up and down, journal sections journaled to said bearings and armatures, and crank arms connected for adjustment with 25 said journal sections to provide adjustable cranks for alternately raising said armatures.

4. Vehicle controlling apparatus embodying a track armature arranged for the passage of a responsive vehicle device, and 30 laminated longitudinally of the track in planes in which said device moves.

5. Vehicle controlling apparatus embodying a track armature arranged for the passage of a responsive vehicle device, and 35 laminated longitudinally of the track in planes in which said device moves, and supporting and actuating means for said armature having a journal portion extending 40 through the laminæ of said armature.

6. Vehicle controlling apparatus embodying movable magnetic means on the vehicle track for influencing a vehicle carried device, and means for supporting said means from 45 the traffic rails clear of the cross ties thereof, so as to yield and remain in fixed relation with the rails in order to maintain a uniform clearance between said magnetic means and vehicle carried device.

50 7. Vehicle controlling apparatus embody-

ing a non-magnetic casing on the vehicle track, movable magnetic means within said casing to magnetically influence a passing vehicle device, and supporting means for the casing having means for attachment to traffic rails, to hold said casing clear of the cross ties, and providing means for keeping the casing and vehicle carried device within a uniform distance of one another and to provide ample clearance between them at all times. 55

8. Vehicle controlling apparatus embodying movable magnetic means on the track for magnetically influencing a passing influencing device, and a cross bar supporting said means clear of the cross ties and having 60 means for attaching it to the traffic rails, to insure, at all times, ample clearance between said means and device.

9. Vehicle controlling apparatus embodying movable magnetic means on the track 70 for magnetically influencing a passing vehicle device, and a cross bar supporting said means and having clamps for attachment to the traffic rails to support said means clear of the cross ties, and also preventing the 75 rails from spreading, said bar retaining said means in a fixed relation with the traffic rails to assure of a suitable and uniform clearance between said means and device at all times.

10. Vehicle controlling apparatus embodying magnetic armatures on the track for magnetically influencing a passing vehicle device, a non-magnetic casing containing said armatures, and a cross bar supporting said casing above the cross ties of the traffic rails, and provided at its ends with clamps to embrace the base flanges of said rails, in order to provide uniform clearance between said casing and vehicle carried device even though the rails may give under 85 the weight of the vehicle, and to also prevent the rails from spreading. 90

In testimony whereof, I hereunto set my hand and seal this 5th day of October, 1918. 95

ALFRED L. RUTHVEN.
